REFRIGERATION

Milton W. Garland, Waynesboro, Pa., assignor, by mesne assignments, to Frick Company, Waynesboro, Pa., a corporation of Pennsylvania

Filed June 25, 1957, Ser. No. 667,745

2 Claims. (Cl. 62—137)

This invention relates to the care and treatment of commodities of various kinds in order to retain certain characteristics or qualities thereof in a definite state or condition with minimum change and all brought about by the control of temperature and the arrest or retardation of the processes of nature.

The invention also relates to apparatus and equipment by which the above results can be accomplished and more particularly to apparatus for the production of refrigeration for use in connection with foods and other things to enhance their usefulness.

Refrigeration has been used directly to cool as well as to cause water to freeze or congeal to form ice and such ice used for refrigeration purposes. Both water and foods and other things have been cooled by direct contact with refrigerating coils and by air flow or convection and by flow of liquid in a secondary system. Also ice has been produced with one refrigeration system and other things have been produced with a separate and independent system. Ice reserve chilling tanks have been used for the storage of refrigeration in the form of ice so that such refrigeration could be used during peak load conditions by the melting of the ice when the power for producing refrigeration was inadequate. Installations of this type have been used in various refrigeration processes with relatively high capacity peaks required over a few hours for the cooling of milk or its products, for instance, after heat has been added in pasteurization or other treatment.

Ice reserve units have comprised one or more tanks containing water with refrigeration coils therein on the external surface of which ice was formed to a substantial thickness. Such ice has been used during peak load periods. However, plants require ice for other purposes than for actual processing, one such use being the transportation of the product.

The submerged coil ice reserve system has been unsatisfactory because of the expense both to install and maintain, the large space required and its inefficiency.

It is an object of the invention to provide a refrigeration system in which a reserve of ice may be produced and stored and the refrigeration represented by the ice stored will be available when desired for any purpose, as well as to provide such a system which is relatively simple, the cost of which is relatively low, the maintenance relatively small and the efficiency great.

Another object of the invention is to provide a refrigeration system including an ice plant or ice maker, a storage bin or chamber divided into a pair of compartments one for containing water and ice and the other merely for containing ice, and with means for selectively directing ice to the desired compartment; the compartment for containing ice and water having an overflow and means for collecting and using the overflow.

A further object of the invention is to provide suitable controls for causing ice to be produced and supplied to such storage bin or chamber and into the ice and water or other liquid chamber until it is filled whereupon

2

the supply of ice will be diverted into the other compartment until it is filled whereupon the ice production will be interrupted until such time as ice is again required.

Other objects and advantages of the invention will be apparent from the following description taken in conjunction with the accompanying drawings wherein:

Fig. 1 is a perspective illustrating one application of the invention;

Fig. 2, a vertical section on the line 2—2 of Fig. 1;

Fig. 3, a vertical section at right angles to the section of Fig. 2 on the line 3—3 of Fig. 2.

Briefly stated, the present invention includes an ice maker for producing ice, part of which can be used and the remainder stored for use when desired or required.

A chamber is provided into which the ice is delivered from the ice maker, such chamber having a compartment with a tank for ice and water or other liquid and a second compartment for ice alone. A butterfly type control member is located within the chamber for causing the ice to pass into the first mentioned compartment, as long as there is need for ice therein and thereafter the surplus automatically is diverted by said control member to the second or surplus ice storage compartment.

The first mentioned or use compartment which is adapted to contain water or other liquid likewise contains a part of a circuit through which such liquid covered by the ice therein can pass to a spaced location where refrigeration is desired. The tank is provided with an overflow pipe to accommodate overflow of liquid from the tank caused by the supply of ice to the tank. The overflow from the tank is caught in a sump and since the water comprising such overflow has been reduced in temperature, for efficiency it is utilized as make-up water for the ice maker with excess water returned to the tank from which it overflowed. This and the selective diversion and control of the ice in the storage bin are important features of the invention.

With continued reference to the drawing, the present invention embodies an ice maker 10, of any desired character, in which the ice is discharged downwardly onto space bars 11 which separate the ice from any water produced by the defrosting of the ice to cause its release from the body with which it is in contact when produced. Ice passes through orifice 12 while chilled water 13 collects in tank 14 and is discharged through an overflow line 15.

The ice maker is refrigerated through a low pressure line 16, from a control valve or other mechanism 17, on the other or high side of which valve is a receiver 18 supplied with refrigerant through a pipe line 19 from a condenser 20 in which refrigerant is liquified. The condenser 20 is supplied with refrigerant in gaseous form through a line 21 from a compressor 22 connected by a suction line 23 with the low pressure side of the ice maker 10.

Ice from the ice maker is discharged by gravity through the orifice 12 and passes beneath the insulating cover 24, through the inlet 25 of chamber 26 defined by the insulating walls 27. Ice discharged from the ice maker 10 through the opening 25 into the chamber 26 gravitates downwardly and the chamber is provided with a partition 28 dividing it into compartments 29 and 30.

Compartment 29 is adapted to contain water or other liquid 40 and compartment 30 is adapted merely to contain ice. Control means is employed, as for example a butterfly valve control member 31 mounted on a pivot 32 directly above the partition 28. Pivot 32 extends through the wall of chamber 26 and has fixed thereon a gear 33 meshing with a gear 34 and driven by a motor 35, mounted on a shelf 36 supported by a bracket 37 and actuated through a line 38 from a control 39 (Figs. 1 and

3) suspended within the chamber 29. The motor 35 rotates gear 34, causing rotation of gear 33 and the shaft or pivot 32 carrying the valve or control member 31.

When ice from ice maker 10 is supplied to compartment 29, containing liquid 40, the ice will rise or accumulate until it influences the control 39, causing motor 35 to rotate the butterfly valve control member 31 upon its pivot 32 until the member 31 rests in the position shown by dotted line in Fig. 2, whereupon the supply of ice from the ice maker will be deflected by said member 31 into the compartment 30.

Compartment 30 is also provided with a thermostatic control 41 connected by line 42 with the motor compressor 22 of the refrigeration system. After chamber 30 is filled with ice it will influence the control 41 and cause the ice maker to stop its production of ice.

The level of the liquid 40 in the compartment 29 is controlled by an overflow pipe 43 which discharges into a sump 44 in which one end of a pipe line 45 is disposed. Through said pipe line 45 liquid may be used in any desired manner, as for example as make-up water in the ice maker 10.

A pump 46 is driven by a motor 47 to move the liquid through the pipe line 45. Liquid 40 in chamber 29 will be refrigerated and used to produce cooling at another location, by movement of the liquid through a pipe line 48, leading from the compartment 29 and including pump 49 driven by a motor 50. The pump 49 is mounted on a bracket 51 and the motor 50 is mounted on a shelf 52 supported by a bracket 53. The pipe line 48 leads to a space or area within wall structure 54 and a return line 55 leads back to the liquid chamber 29 thereby serving to complete the circuit. The inlet to the lines 43 and 48 is shielded from ice particles by means of a filter 58 including a screen 57.

It will be apparent from the foregoing that ice from the ice maker, when it is in operation, will be discharged into the ice chamber 29 until the ice influences the control 39 whereupon the motor 35 will rotate the pivot 32 and the control valve 31 to cause the ice to be supplied to the chamber 30 until it influences the control 41 to discontinue the operation of the ice maker or shut down the refrigeration system until such time as ice is again required.

Liquid within the chamber 29 will overflow through the pipe 43 into the sump 44, and by means of the pump 46 driven by the motor 47 the liquid will be forced through the pipe line 45. Liquid 40 within the chamber 29 will be pumped through the line 48 by means of the pump 49 and motor 50 to the space within the wall structure 54, such circulation being likewise subject to a control 56, return from the space to be refrigerated being provided through the pipe 55.

It is understood, of course, that only one embodiment of the invention is illustrated. The control 41, as pointed out, is for the purpose of governing operation of the ice maker 10 and may obviously control either a refrigeration system element, such as a compressor, or may control the supply of refrigerant to the ice maker without necessarily shutting down the refrigeration system. Furthermore, the refrigeration elements 16-21 are merely illustrative, and it is contemplated that a system such as that described in my application Serial Number 531,017, entitled Ice-Making Apparatus, may be used for the production of ice.

It will be obvious to those skilled in the art that various changes may be made in the invention without departing from the spirit and scope thereof and therefore the invention is not limited by that which is illustrated in the drawings and described in the specification, but only as indicated in the accompanying claims.

What is claimed is:

25 1. A refrigeration system comprising an ice maker, wall structure defining a chamber into which ice from said ice maker is discharged, said chamber having a liquid compartment and an ice storage compartment, means for circulating overflow liquid from said liquid compartment to said ice maker, means responsive to the accumulation of ice in said liquid compartment for selectively directing ice from said ice maker into either of said compartments, and means responsive to the accumulation of ice in said ice storage compartment for controlling the 30 operation of said ice maker.

2. A refrigeration system as defined in claim 1, and means for circulating liquid from said liquid compartment to a heat load for refrigeration of the latter and for returning said liquid to the liquid compartment.
